UNITED STATES PATENT OFFICE.

ALBERT H. KENNEWEG, OF BROOKLYN, NEW YORK.

RAILWAY DRAFT GEAR.

Application filed January 20, 1926. Serial No. 82,542.

This invention relates to a railway draft gear and more particularly to cushioning mechanism therefor.

An object of the invention is to provide an apparatus that will fit within the pocket of the standard railway draft gear designed to absorb the shocks produced by a force applied to the draw bar in either direction.

A further object is to provide an apparatus in which the springs employed are placed under tension when a force is applied to the draw bar.

A further object is to provide a novel type of spring construction together with means for exerting a pull on the spring when a force is applied to the draw bar in either direction.

In the accompanying drawings, I have shown several embodiments of the invention.

20 In this showing,—

Figure 1 is a perspective view of the device removed from the draft gear, parts being shown in section,

25 Figure 2 is a longitudinal sectional view substantially on line 2—2 of Figure 3,

Figure 3 is a transverse sectional view substantially on line 3—3 of Figure 1,

30 Figure 4 is a side elevation of the inner face of one side of the U-shaped connecting member,

Figure 5 is a plan view,

35 Figure 6 is a plan view of a modified form of the invention,

Figure 7 is a longitudinal sectional view on line 7—7 of Figure 6, and,

Figure 8 is a detail sectional view on line 8—8 of Figure 7.

Referring to Figures 1 to 5 of the drawings, the reference numeral 1 designates a casing shaped to fit within the pocket of a standard railway draft gear. Within the casing I provide a plunger 2 having a flat front face 3 against which the rear end of the draw bar is adapted to abut. As will be readily understood by those skilled in the art, the yoke of the draft gear, which is connected to the draw bar, will extend around the casing 1. Within the casing I provide a substantially U-shaped connecting member consisting of a pair of parallel arms 4 arranged on opposite sides of the plunger and a base 5. The free ends of the arms are connected by a pin 6 (see Fig. 3) which extends through an elongated slot 7 in the plunger. The connecting member 4 and the plunger are connected to each other by a

number of springs 7, two being shown in this instance on each side of the plunger. The inner faces of the arms 4 are provided with projections 8 adjacent their forward ends (see Fig. 4) and the sides of the plunger are provided with similar projections 9 (see Fig. 2), adjacent their rear ends. As shown the springs are substantially circular in shape and are provided with lateral extensions 10 at each end adapted to receive the projections 8 and 9.

The construction shown in Figures 6 to 8 of the drawings, is substantially the same as that heretofore described except that a modified form of spring is employed. Instead of employing a plurality of separate springs as shown in Figures 1, 2 and 5, I employ a single spring 11 on each side of the plunger and this spring is arranged in as many coils as desired. The ends of the spring are extended substantially parallel to each other as at 12 and are provided with hooks 13 on their ends. A connecting ring 14 is placed over these hooks as shown in Figures 7 and 8 to secure the spring in position.

In the operation of the form of the device shown in Figures 1 to 5 of the drawings, when the draw bar moves backwardly against the face 3 of the plunger 2, the plunger is moved rearwardly in the casing. As shown (see Fig. 5) the rear end of the plunger is spaced from the base 5 of the connecting member and the elongated slot 7 permits independent movement of the plunger. This rearward movement of the plunger moves the rear end of the springs through the projections 9 and thus tends to straighten the springs or place them under tension. Likewise, when a pull is exerted on the draw bar the springs are placed under tension. The yoke of the standard draft gear (not shown) which extends in the rear of the casing 1 engages the base 5 of the connecting member 4 to move the connecting member 4 forwardly without moving the plunger. This increases the distance between the two ends 10 of the spring through the engagement of the forward ends with the projections 8 and thus places the springs under tension.

The operation of the form of the device shown in Figures 6 to 8 of the drawings, is essentially the same and when force is applied to the draw bar in either direction the distance between the projections 8 and 9,

and thus the distance between the two ends of the spring, is increased to place the spring under tension.

By employing a tension spring instead of 5 the usual type of compression spring a greater cushioning effect may be obtained in the limited space provided and a construction is produced which may be employed in connection with a standard draft gear without modifying the construction of 10 the draft gear.

It is to be understood that the forms of 15 my invention herewith shown and described are to be taken as preferred examples of the same, and that various changes in the shape, size, and arrangement of parts may be resorted to without departing from the spirit of the invention or the scope of the subjoined claims.

20 I claim:

1. In a device of the character described, a plunger arranged in alinement with the draw bar and independently movable with respect thereto, said plunger being adapted 25 to be actuated by a rearward movement of the draw bar, a connecting member extending rearwardly of the plunger and adapted to be actuated by a forward movement of the yoke, and a tension spring connecting 30 said members.

2. In a device of the character described, a casing adapted to be arranged in the pocket of a standard railway draft gear, a plunger mounted in said casing and abutting 35 the draw bar whereby rearward movement of the draw bar will be transmitted to said plunger, a connecting member mounted in said casing and extending rearwardly of the plunger, said connecting member being 40 adapted to be actuated by forward movement of the yoke of the draft gear, and a tension spring connecting said plunger and said connecting member.

3. In a device of the character described, 45 a plunger adapted to be actuated by a rearward movement of the draw bar, a substantially U-shaped connecting member surrounding said plunger, means for actuat-

ing said connecting member upon forward movement of the draw bar, and a tension 50 spring connecting said plunger and said connecting member.

4. In a device of the character described, a casing adapted to be arranged in the pocket of a standard railway draft gear, a 55 plunger mounted in said casing and abutting the rear end of the draw bar whereby rearward movement of the draw bar will be transmitted to said plunger, a substantially U-shaped connecting member mounted in 60 said casing and surrounding the draw bar, means for transmitting forward movement of the draw bar to said connecting member, and a tension spring connecting said plunger and said connecting member.

5. A device constructed in accordance with claim 1 wherein said plunger is provided with a projection adjacent one end and said member is provided with a projection adjacent its opposite end to receive said spring. 70

6. A device constructed in accordance with claim 2 wherein said spring comprises a substantially circular member having diametrically opposed extensions and said plunger and said connecting member are provided with projections adjacent their opposite ends adapted to receive said extensions. 75

7. In a device of the character described, a casing adapted to be arranged in the pocket of a standard draft gear, a plunger mounted in said casing and abutting the rear end of the draw bar whereby rearward movement of the draw bar is transmitted to said plunger, a substantially U-shaped connecting member mounted in said casing adjacent the plunger and adapted to be actuated by forward movement of the draw bar, said plunger being provided with lateral projections adjacent one end, the adjacent faces of said connecting member being provided with lateral projections adjacent the other end, and a substantially circular tension spring mounted on said projections. 85 90

In testimony whereof I affix my signature.

ALBERT H. KENNEWEG.
